MOUNT FOR FLEXIBLE SYNCHRONIZED GUNS.

Application filed April 18, 1922. Serial No. 555,415.

This invention relates to a flexible mount for a synchronized aircraft machine gun.

The object of the invention is to produce a flexible mount which is adapted to permit adjustment of the gun during the firing operation in synchronism with the propeller, and which will advance or retard the time of the firing impulses when the gun is shifted to the left or to the right. The mechanism 10 is also adapted to decrease the amount of lead in the timing when the gun is pointed so as to bring the line of fire nearer to the hub of the propeller.

With the above and other objects in view, 15 the invention consists in the novel construction, combination and arrangement herein fully described, illustrated and claimed.

In the accompanying drawings:

Figure 1 is a view partly in side elevation 20 and partly in section of the improved flexible gun mount.

Figure 2 is a plan view of the same.

Figure 3 is an end view thereof.

Figure 4 is a view partly in side elevation 25 and partly in section of the time-controlling mechanism of the impulse generator.

Figure 5 is an elevation thereof taken at a right angle to Figure 4.

Figure 6 is a cross section on the line 30 6-6 of Figure 4.

Referring to the drawings, the gun mount embodies a frame which is bolted or otherwise fastened to the gun in fixed relation thereto. Said frame, in the preferred embodiment of the invention, comprises a pair of side plates 1 arranged in spaced relation to each other and suitably connected together by bolts or tie members as shown in Figures 2 and 3.

The frame above referred to is fastened to the gun at its trunnions and the side plates are pivotally connected to the horizontal lateral pin 2 carried by a normally vertical rotatable stub shaft 3, the latter being journaled in a bearing 4 in eccentric relation to a threaded shaft 3', supported rigidly in a bearing 5 of a bracket 6.

The bracket 6 is adapted to be fastened to any suitable supporting base and is held stationary. A vertical control pin 7 slideable through a bearing sleeve 8 is supported between the plates 1, the sleeve 8 being sustained by cross members 9. A segmental or

sector control gear 10 is rotatably mounted between adjusting nuts on the threaded 55 shaft 3 and embodies a longitudinally grooved arm 11 in which is inserted a ball or spherical head 12 on the lower end of the control pin 7, the ball 12 being slideable along the groove of arm 11.

The gear 10 meshes with a pinion 13 adjustably secured on a vertical threaded shaft 14 journaled in bearings 15 and 16 in the bracket 6. The lower end of the shaft 14 in conjunction with a threaded nipple 17 60 is adapted to receive one end of a flexible shaft 18 leading to the impulse generator 19, shown in Figure 4. The other end of the flexible shaft 18 is coupled to a worm shaft 20 journaled in a housing 21 and forming 65 a part of the impulse generator assembly. Fast on the shaft 20 is a worm gear 22 which meshes with a sliding worm rack face 23 on one side of an adjustable sleeve 24, the latter surrounding the shaft 25 of the 70 impulse generator.

The impulse generator shown in Figure 4 is of the Nelson type, modified. The shaft 25 is divided into upper and lower sections 26 and 27 respectively, the ends of which 80 abut as shown in Figure 4. The shaft sections 26 and 27 are relatively adjustable axially. To this end the shaft sections 26 and 27 are formed with spiral ways or 85 grooves 28 and 29 which are reversely inclined. That is to say one of the ways is a right hand spiral and the other a left hand spiral. The sleeve 24 carries internally projecting pins 30 and 31 which work in the grooves 28 and 29. An expansion 90 spring 32 resists the downward movement of said sleeve 24.

The operation of the mechanism hereinabove described is as follows. When the gun is adjusted around the axis of the shaft 3, 95 the control pin 7 operating through gears 10 and 13 causes a partial rotation of the shaft 14 and this motion is communicated through the flexible shaft 18 to the worm gear 22. Through the medium of the rack face 23, the worm gear causes a downward or upward movement of the sleeve 24 with the result that the shaft section 25 of the impulse generator is turned through a given 100 arc with respect to the shaft section 27. In 105 the drawing the sleeve is shown moved to

an extreme upward position. It will normally occupy a halfway position with the gun horizontal and directed straight ahead parallel to the fore and aft axis of the ship. 5 This shifting of the relation of the shaft sections changes the timing of the impulse generator giving sufficient lead to prevent the bullets from striking the propeller blades during the firing of the gun in this 10 laterally adjusted position. That is, the time of firing is advanced on deflection of the gun to the left and is retarded on deflection to the right of a central straight ahead position, assuming the firing point to 15 be beyond the propeller positions. On the other hand, when the gun is adjusted vertically while pointing in its normal direction of aim, the ball 12 on the control pin 7 slides along the arm 11 of the gear 10 and 20 effects no adjustment of the generator shaft since that is not necessary during such adjustment of the gun. Should the gun be adjusted laterally and vertically, the timing is advanced and retarded to different extents 25 depending on the proximity of the firing with the propeller hub. If the aim is closer to the hub, less lead is given in advancing or retarding the timing of firing as the case may be, than when the aim is more toward 30 the tip of the propeller. The reason for this is apparent, since the area included between two positions of a propeller blade is triangular or segmental in form, that is, as you approach the hub, there is less and less latitude 35 for firing without hitting the propeller blade, as the free or "safe" area becomes more and more restricted. Of course the firing can in no case approach the hub very closely due to the presence of obstructions 40 between the gun and the propeller, so that relatively only a small correction in lead is necessary so far as safely firing through the propeller is concerned.

The arrangement of the gun mount as a 45 unit revolving on a swivel eccentric to the axis of revolution of the arm 11 enables giving a different lead to the firing when the gun is elevated, from that when the gun is depressed, where the firing is not directly 50 straight ahead, as, in that case no variation in timing is needed, as was stated before. This eccentricity which is necessarily only slight, is shown in Fig. 1 where the stub shaft 3 is off center, relative to the shaft 3', and 55 is displaced to the front. This arrangement, it will be seen, causes a lesser angular movement to be communicated to the arm 11 when the gun is depressed, because the ball end 12 of the pin 7 is closer to the shaft 3 about which the gun mount turns. When 60 the gun is elevated the arm 11 is given a greater angular movement with a given angular movement of the gun mount, since in that case the ball end 12 of the pin 7 operates farther out in the guide on the arm 65

11, the ball end being farther removed from the shaft 3. If the shaft 3 and shaft 3' were coaxial, it is obvious they would turn through an equal angle no matter how far removed the ball end 12 was from the shaft 3, but it is the eccentricity of the shaft 3 relative to the shaft 3', which produces the operation described. Thus, a smaller advance or retard in the time of firing is made when the gun is aimed closer to the propeller hub than is the case when the aim is toward the tip of the propeller. 70 75

The adjustment of the arm 11 with the sector gear 10 and gear 13 on the shafts 3' and 14 respectively, enables changing the 80 extent of the correction in lead in the firing for different propellers. When the arm 11 is brought up closer to the gun mount the pin 7 is confined to operating within a smaller 85 range in the guide in the arm 11, than is the case when the arm 11 is lowered away from the gun mount. Thus a smaller extent of change in lead will result when the arm 11 is brought closer to the gun mount. 90

Having thus described our invention, we claim:

1. The combination of a machine gun, a flexible mount therefor, an impulse generator, and means dependent upon the vertical angular movement of said flexible mount for automatically varying the timing of the impulses of said generator in proportion to the up and down movement of the gun to decrease or increase the amount of lead in the firing when the gun is pointed closer to or 100 farther from the propeller hub. 95

2. A flexible mount for a synchronized machine gun having means to permit adjustment of the gun during firing in synchronism with the propeller, and also having means dependent upon the vertical angular movement of said flexible mount to decrease or increase the amount of lead in the timing when the gun is revolved about a horizontal axis to bring the line of fire nearer to or farther from the hub of the propeller, and to advance and retard the timing when the gun is swung to the right and left. 110 105

3. In combination, a gun mount pivotally mounted on a support, a flexible means on said gun mount and said support adapted to transmit and vary motion of said gun mount to said flexible shaft, a worm on said flexible shaft, a rack operable by said worm, two studs on said rack each slidably engaging one shaft portion of a two part impulse shaft in a helical slot therein, the two said slots being cut with opposite inclines, the rotation of said worm governing the relative positions of the two portions of said impulse shaft. 115 120 125

4. In combination, a gun mount pivotally mounted on a support, a flexible shaft, means on said gun mount and said support adapted to transmit and vary motion of said gun 130

mount to said flexible shaft, a two part impulse shaft, and means operable by said flexible shaft to govern the relative positions of the two portions of said impulse shaft for the purpose described.

5. In combination, a flexible gun mount carried by a support, an impulse shaft, a flexible connection between said gun mount and said impulse shaft for transmitting motion of the former to the latter, and means forming a part of said flexible connection whereby proportional and differential movements are given said impulse shaft in different positions of said gun mount.

10 6. In combination a flexibly mounted gun, an impulse generator and means to retard or advance said generator in deflections of said gun mount, said means operating to effect different retarding or advancing of said generator when the gun is elevated or depressed.

15 7. In combination, a flexible gun mount turning on a swivel support, an impulse generator, means to advance or retard the impulse generator in the traversing of said gun mount, and means turning on a center eccentric to said gun mount swivel support for transmitting differentially the turning movement of said gun mount to said last mentioned means.

20 8. In combination, a flexible gun mount turning on a swivel support, an impulse generator, means to advance or retard the impulse generator in the traversing of said gun mount, and means turning on a center eccentric to said gun mount swivel support for transmitting differentially the turning movement of said gun mount to said last mentioned means, the extent of movement transmitted varying with the degree of elevation 40 of the gun.

25 9. In combination, a flexible gun mount turning on a swivel support, an impulse generator, means to advance or retard the impulse generator in the traversing of said gun mount, and means turning on a center eccentric to said gun mount swivel support for transmitting differentially the turning movement of said gun mount to said last mentioned means, a relatively greater 50 amount of movement for a given angular movement of said gun mount being transmitted to said last mentioned means when the gun is elevated than when the gun is depressed.

30 10. In combination, a flexible gun mount carried on a swivel support, a follower for said gun mount oscillating on an axis eccentric with said swivel, an impulse generator and means for transmitting the angular 60 movement of said follower to said impulse generator to advance and retard the timing of firing according to the position of said gun mount.

35 11. In combination a flexible gun mount carried on a swivel support, a guide member

acting as a follower for the gun mount oscillating on a center eccentric to said swivel support, a pin slidably received in said gun mount having an end bearing in said guide, in all positions of elevation and depression of the gun to transmit angular movement of said gun mount to said guide, an impulse generator and means for transmitting movement of said guide to said impulse generator to advance and retard the timing of 70 firing according to the position of said gun mount.

12. In combination, a flexible gun mount carried on a swivel support, a guide member acting as a follower for the gun mount 80 oscillating on a center eccentric to said swivel support, a pin slidably received in said gun mount having an end bearing in said guide, in all positions of elevation and depression of the gun to transmit angular 85 movement of said gun mount to said guide, an impulse generator and means for transmitting movement of said guide to said impulse generator to advance and retard the timing of firing according to the position of 90 said gun mount, the degree of advancing and retarding depending on the position of said pin in said guide, in the elevation and depression of said gun mount.

13. In combination, a flexible gun mount 95 operating on a vertical swivel, a sector gear operating on an axis eccentric to said swivel and displaced to the rear thereof relative to the gun mount, a gear turned by said sector, an impulse generator connected with 100 said gear and an arm for operating said sector in the lateral swinging of said gun mount.

14. In combination, a flexible gun mount 105 operating on a vertical swivel, a sector gear operating on an axis eccentric to said swivel and displaced to the rear thereof relative to the gun mount, a gear turned by said sector, an impulse generator connected with 110 said gear, an arm for operating said sector, and a vertically sliding pin on said gun mount having its lower end slidably engaging said arm to transmit swinging movement thereto in the movement of the gun mount.

15. In combination, a flexible gun mount 115 operating on a vertical swivel, a sector gear operating on an axis eccentric to said swivel and displaced to the rear thereof relative to the gun mount, a gear turned by said sector, an impulse generator connected with 120 said gear, and a vertically sliding pin on said gun mount having its lower end slidably engaging said arm to transmit swinging movement thereto in the movement of the gun mount, communicating more or less angular movement of said gun mount, depending on the elevation or depression of the gun which causes said pin to operate at different 125 positions in or out on said arm.

16. In combination, a flexible gun mount 130

operating on a vertical swivel, a sector gear and means for adjusting said arm toward operating on an axis eccentric to said swivel and away from said gun mount. and displaced to the rear thereof relative to the gun mount, a gear turned by said 10 to the gun mount, a gear turned by said 5 sector, an impulse generator connected with said gear, an arm for operating said sector in the lateral swinging of said gun mount,

HERBERT O. RUSSELL.
CHARLES LEIGH PAULUS.
